UNITED STATES PATENT OFFICE.

HENRY SPERLING, OF JERSEY CITY, NEW JERSEY.

FIRE-ESCAPE.

SPECIFICATION forming part of Letters Patent No. 693,533, dated February 18, 1902.

Application filed June 19, 1901. Serial No. 65,093. (No model.)

To all whom it may concern:

Be it known that I, HENRY SPERLING, a citizen of the United States, and a resident of Jersey City Heights, Hudson county, New Jersey, have invented certain new and useful Improvements in Fire-Escapes, of which the following is a specification.

This invention relates to a fire-escape composed of a folding ladder, such as described in Patent No. 645,982, granted to me March 27, 1900. By the present invention I have devised means for relieving the winches for raising the ladder from excessive strain and for so distributing the power that the ladders may be raised without undue effort on the part of the firemen.

In the accompanying drawings, Figure 1 is side elevation of the fire-escape, showing the ladder lowered. Fig. 2 is a horizontal section on line 2 2, Fig. 1; Fig. 3, a longitudinal section through the post h h^2 ; Fig. 4, a side view of the lower portion of the post; Fig. 5, a cross-section on line 5 5, Fig. 3; Fig. 6, a side view of the lower end of one of the rods m ; Fig. 7, a section on line 7 7, Fig. 6; Fig. 8, a side elevation of the fire-escape, showing the ladder partly raised; and Fig. 9, a front view, partly in section, of one of the ladders r .

The letter a represents the platform of the fire-escape mounted upon wheels, as usual. From the platform projects upwardly a standard b , to which is hinged the lowermost section b' of a folding ladder b' b^2 , shown to be composed of two sections, though it may obviously be made with additional sections. The uppermost section b^2 is provided with an arch or segment b^3 , as more fully described in my Patent No. 645,982, above referred to. Over this arch pass a pair of ropes c d , of which the rope c leads from the back of the arch to a front winch e , while the rope d leads from the front of the arch to a rear winch f . By turning the winch e the ladders b' b^2 will be raised off their support g into an approximately upright position, Fig. 8, and by then turning the winch f the top section b^2 will be raised vertically above the bottom section b' , so that the ladder is completely unfolded.

In order to facilitate the above operation of raising the ladder and to relieve the winches from excessive strain, I have devised the following construction: To the upper end

of the ladder-section b' is hinged at h' the upper member h of a telescoping post. The lower hollow member h^2 of this post carries at its lower end a roller h^3 , which runs between a pair of rails h^4 h^5 , of which the upper rail h^4 forms a stop for limiting the movement of the roller. When the ladder is lowered, Fig. 1, the post is telescoped and in an inclined position. Therefore when the post is first righted and then distended it will tend to gradually raise the ladder. In order to righten the post, it is connected at its lower end by a rope l to a rear winch k . By turning this winch the roller h^3 will be moved along the rail h^4 toward the rear of the platform, and thus the post will be gradually righted. The turning of the winch k should take place simultaneously with the turning of the winch e , so that the ladder is pulled and pushed at the same time into an inclined position. By now distending the telescoping post the lower section b' of the ladder will be swung still farther into an upright position. This distention of the post is effected by means of a winch j on post-section h^2 , which raises post-section h by means of a rope i running over pulley i' . The pulley i' is secured to the upper end of the section h^2 and the rope i is secured to the base of section h , so that upon turning the winch j the section h will be gradually drawn out of section h^2 . In this way the simultaneous manipulation of first the winches e and k and then of the winches e and j will effect the righting of the lower ladder-section b' into the position shown in Fig. 8. After the ladder has been brought into this position the upper section b^2 is righted by the winch f ; but here again additional means should be provided for relieving the winch from excessive strain. These means consist of a pair of rods m , the upper ends m' of which are forked or hooked to removably engage a cross-piece b^4 at the free end of section b^2 . The lower ends of rods m carry rollers m^2 , movable between rails n n' . These rails extend along the platform a to the right and left of the rails h^4 h^5 . In order to move the base of rods m along the rails n n' , I employ a front winch p , connected to the lower ends of the rods by ropes q q .

If the ladder b^2 is to be raised, the upper ends of the rods m are hooked into the cross-

piece b^4 , while the rods are inclined and the rollers m^2 are in their rearmost position, Fig. 8. By now turning the winch p simultaneously with the winch f the rods m will be gradually raised into an upright position, so that the ladder is started and the winch f is relieved and can fully raise the ladder.

It will be seen that by the coöperation of the winches the several sections of the folding ladder may easily be raised and that an excessive amount of power at any one point is obviated.

I prefer to provide the main ladder with a number of auxiliary ladders r , Fig. 8, which may be thrown out in a horizontal or slanting direction, so as to reach the windows. These ladders are made extensible, Fig. 9, being provided with an upper sliding section r' , that may be raised and lowered by means of a winch s and rope t , running over roller t' . The ladder r is swiveled at r^2 to a platform b^5 of ladder b' , so that it can be turned in any direction desired.

What I claim is—

25 1. A fire-escape composed of upper and lower ladder-sections hinged together, ropes and winches for raising the sections; combined with auxiliary raising means consisting of an extensible post to engage the lower section and sliding rods to engage the upper section, whereby the ropes and winches are relieved of excessive strain, substantially as specified.

2. A fire-escape composed of upper and lower ladder-sections hinged together, means 35 for raising the sections, auxiliary raising means to relieve the first-named means of excessive strain, said auxiliary raising means consisting of a telescopic sliding post hinged to the lower section, and sliding rods removable engaged by the upper section, and means to right the post and rods.

3. A fire-escape having a platform, two hinged ladder-sections mounted thereon, means for raising and keeping the position of 45 the lower section, guide-rails secured to the platform, sliding rods having rollers at one end to engage the rails and adapted to removably engage the upper ladder-sections at their other ends, and means on the platform 50 for raising the upper sections and righting the rods, substantially as specified.

4. In a fire-escape, the combination of two hinged ladder-sections, ropes and winches for raising the sections, sliding rods to removably engage the upper section, rollers journaled in the rods, rails to confine the rollers, and winches for raising the rods, substantially as described.

Signed by me at New York city, county and 60 State of New York, this 18th day of June, 1901.

HENRY SPERLING.
